UNITED STATES PATENT OFFICE

HANS RIES, OF MUNICH, GERMANY.

GAS-RETORT FURNACE.

No. 926,135.

Specification of Letters Patent.

Patented June 29, 1906.

Application filed July 9, 1907. Serial No. 382,883.

To all whom it may concern:

Be it known that I, HANS RIES, a citizen of the Empire of Germany, residing at Munich, Germany, have invented certain new and useful Improvements in Gas-Retort Furnaces; and I do hereby declare the following to be a full, clear, and exact description of the invention, such as will enable others skilled in the art to which it appertains to make and use the same.

This invention relates to retort furnaces specially suitable for the manufacture of coal gas and particularly to furnaces of the type having inclined chambers or retorts which are charged from the rear. This method of charging is, for instance, required in cases where there are two or more superposed series of chambers so that the lower walls of the upper chambers form the roofs or upper walls of the chambers situated below them.

The object of the invention is to enable the chambers to be completely charged up to their roof and to regulate the heating of the chambers in such a manner that not only is the gas which collects in the upper portion of a chamber prevented from becoming decomposed but also the bottom of the chamber is sufficiently heated without providing heating conduits in it.

A construction of furnace is illustrated in the drawings, in which,

Figure 1 is a vertical longitudinal section of the furnace on line 1—1 of Fig. 2, Fig. 2 is a vertical section on line 2—2 of Fig. 1, Fig. 3 is a vertical longitudinal section through the upper portion of the furnace on line 3—3 of Fig. 2, and Fig. 4 shows one half of a horizontal cross-section on line 4—4 of Fig. 3.

As will be seen from the drawing, the roofs b of the chambers or retorts a are formed higher at the upper ends of the chambers so that an additional space c is formed in the upper part of the chamber above the line followed by the greater part of the roof b.

Into this widened portion c opens the laterally arranged charging shaft d through which the coal or other material to be distilled is fed. Owing to the arrangement of the widened portion c in the highest portion of the chambers a it is possible to fill the chambers completely with the material which is introduced in an oblique direction through the charging shaft d. The space c is also used as gas collecting space to which a rising or ascension pipe (not shown in the drawing) for discharging the gas is connected.

When the lateral walls and roof of the chamber a are heated in a uniform manner, the space c is at the same temperature as the other walls. This is disadvantageous since the heavy hydrocarbons of the gas generated become decomposed by the hot walls of the collecting space c. In order to avoid as far as possible such decomposition of the gas in the interior of the space c, the conduits for the heating gases are arranged in the following manner. The chambers a which are arranged side by side (three are shown in the example illustrated) are separated from each other by the vertical flues or conduits e and f, and from the lateral walls g and h of the furnace, by the vertical flues i and j. The flues e and i and f and j are connected together at the top by transverse roof conduits k. As will be seen in Fig. 1, these roof conduits k are, however, arranged only in the lower and central portions of the roof b, while the lateral conduits e f i j adjoining the upper portion of the roof b are connected to conduits n provided in the back wall m of the furnace which at the same time is the rear wall of the retort. This connection is effected by providing the partitions in the upper portion of the flues e f i j adjoining the space c, with perforations o which connect these flues to the conduits n (Figs. 3 and 4) provided in the back wall m. Owing to this method of conducting the heating gases, a direct heating of the gas collecting space c is avoided, and thus a decomposition of the gas collecting in that space is obviated, and also the back wall m of the furnace is in that way heated directly, so that coals resting against it are completely distilled.

The lateral walls of the furnace chambers a rest upon laterally projecting bottom walls or stones p carried by vertical pillars r which preferably extend down to the foundations of the furnace so that the weight of the chambers a and of their charge is transmitted direct to the foundations.

Below the bottom walls p supporting the chambers a on the pillars r are arranged conduits s for heating gases separated by a partition u from air conduits t. The partition u terminates immediately below the projecting portion of the lower walls p. Consequently the combustion of the heating gases takes place in the space laterally limited by the bottom wall p above the free end of the partition u, so that at that point

is situated the hottest combustion zone, the heat of which is transmitted by the bottom walls *p* to the bottom of the chambers *a*. In that way the bottoms of the chambers *a* are heated to a sufficient extent without it being necessary to arrange heating conduits in them which greatly affect the durability of the chambers. Moreover, owing to the combustion of the heating gases taking place in the space between the bottom plates *p*, the lateral walls of the chambers *a* are less damaged for the bottom series of bricks constituting the lateral walls of the chambers are already outside the hottest combustion zone. The bottom walls *p* themselves are made sufficiently strong and durable to resist the high temperatures to which they are subjected.

10 The air for combustion carried in the conduits *t* is subjected in well known manner to preliminary heating by means of the regenerator arranged in the bottom portion of the furnace, which receives its heat from the gases which escape from the condits *i j*.

15 25 Constructional details of the furnace described can of course be modified according to different circumstances without departing from the spirit of the invention, for instance two or more series of furnace chambers can 30 be arranged above each other, so that the roof of one series of chambers forms the bottom of the one immediately above it. Then can also be any desired number of chambers arranged side by side.

35 35 What I claim is:—

1. In a gas retort furnace the combination of an inclined retort having an upward extension, or enlargement at its upper end and a charging shaft connected with said retort 40 at the enlargement thereof.

2. In a gas retort furnace the combination of an inclined retort having an inclined enlargement at its upper end and an inclined charging shaft opening into said enlargement 45 and ranging lengthwise of the retort.

3. In a gas retort furnace a retort inclined upwardly from front to rear and having its roof solid at the upper portion and provided with transverse channels at its central and lower portions, the rear wall of the retort being provided with transverse channels at its upper end.

4. In a gas retort furnace the combination with inclined chambers having upward and downward heating channels along their respective side walls, cross channels connecting said upward and downward channels and located in the roof of the retort at its lower and central portions and cross channels connecting the upward and downward channels at the upper portion of the retort, the latter named cross channels being located in the rear wall of the retort.

5. In a gas retort furnace an inclined retort having upward and downward heating channels along its respective sides, the roof of said retort being solid at its upper portion and provided at its lower and central portions with cross channels connecting the adjacent upward and downward channels, those upward and downward channels which are near the upper portion of the retort being separated by perforated partitions, and the rear wall of the retort adjacent to its upper end being provided with transverse channels connected with the last-named upward and downward channels.

6. In a gas retort furnace, an inclined retort having an upward extension or enlargement at its upper end, the roof of said retort being solid at the portion where such enlargement is provided, while the central and lower portions of the retort roof are provided with transverse heating channels.

In testimony whereof I hereunto affix my signature in the presence of two witnesses.

HANS RIES.
